UNITED STATES PATENT OFFICE.

JAMES S. PRINGLE, OF RICHLAND, IOWA.

GATE-HANGER.

SPECIFICATION forming part of Letters Patent No. 322,556, dated July 21, 1885.

Application filed April 19, 1884. (No model.)

To all whom it may concern:

Be it known that I, JAMES S. PRINGLE, a citizen of the United States of America, residing at Richland, in the county of Keokuk 5 and State of Iowa, have invented certain new and useful Improvements in Gate-Hangers, of which the following is a specification, reference being had therein to the accompanying drawings.

10 My invention relates to adjustable gates; and it consists in certain details of the construction and operation of the several parts, as will be hereinafter more fully set forth in the specification, and pointed out in the accompanying drawings, in which—

Figures 1 and 2 are side elevations of my improved gate; Fig. 3, a section of the same on the line $x-x$, Fig. 2, and Fig. 4, a detail perspective view of the spring-hinge.

20 The object of the invention is to provide a gate that is vertically adjustable, and at the same time can be turned at right angles to the plane of its closed position or can be moved back directly in said plane.

25 The better to explain its construction and operation, I will now refer to the drawings and the letters of reference marked thereon.

I use the ordinary gate-posts, to one of which, A, I secure the locking-cleats a , and 30 to the other, A', the hook O and the eyebolt or staple E'. The gate-panel B has one board or plank, b, extending outward beyond the edge of the panel to rest in the cleat a , as shown in Figs. 1 and 2.

35 To provide for the adjustment and movement of the gate, I use the spring-hinge C, made of spring metal bent and perforated in the center, as shown in Fig. 4, and having

the ends c brought together in the form of a point. At the lower part or end of the hinge 40 a roller, d, is journaled for the longitudinal pieces of the gate to roll on. The hinge can be taken out from its bearings by simply lifting it up until pivot e of the bolt E is free, and then slipping it down so as to remove the 45 point from eyebolt E'.

In Fig. 1 the gate is shown as hung in its normal position or quite near the ground. In Fig. 2 it is shown raised up to accommodate the snow. In Fig. 1 the spring-hinge 50 supports the second plank from the bottom, and in Fig. 2 the lower plank rests on the roller in the hinge. It is apparent that the gate can be rolled directly back in its own plane or can be swung around at right angles. 55

Having thus described my invention, what I claim is—

The combination, with a gate, of a hanger, C, consisting of a strip of spring metal bent 60 at the center and provided thereat with a roller, and with a pivot-hole to receive a hook-bolt in the gate-post, the opposite end of said hanger forming a neck for insertion in an eye-bolt, the hanger being removably seated in 65 said bearings whereby it may be placed underneath any bar of the gate, thereby rendering the gate vertically adjustable, substantially as and for the purpose set forth.

In testimony whereof I affix my signature, 70 in presence of two witnesses, this 24th day of April, 1883.

JAMES S. PRINGLE.

Witnesses.
